UNITED STATES PATENT OFFICE.

EDWARD O. GOSS, OF WATERBURY, CONNECTICUT, ASSIGNOR TO SCOVILL MANUFACTURING COMPANY, OF WATERBURY, CONNECTICUT, A CORPORATION OF CONNECTICUT.

MACHINE FOR COILING METAL.

No. 927,037.

Specification of Letters Patent.

Patented July 6, 1909.

Application filed January 7, 1908. Serial No. 409,706.

To all whom it may concern:

Be it known that I, EDWARD O. GOSS, a citizen of the United States, residing at Waterbury, in the county of New Haven and State of Connecticut, have invented a certain new and useful Improvement in Machines for Coiling Metal, of which the following is a full, clear, and exact description.

This invention relates to machines for coiling metal, and more particularly to an attachment for a sheet-metal rolling-machine.

The object of the invention is to provide an attachment for a rolling-mill for rolling sheet-metal, whereby the metal may be taken directly from the rolling-mill and automatically coiled or blocked into suitable coils or rolls.

The invention consists essentially of mechanism for stripping the metal from the rolls and guiding it thence to a coiling or blocking mechanism, mounted upon a carriage which is capable of being moved toward and from the stripping mechanism, the coiling or blocking mechanism being actuated to form an initial lap of metal on its winding-drum as it comes from the rolls and coil it upon the drum, without direct handling of the metal by the operator, and then loosen up the coil so that it may readily be removed from the winding-drum, all as I will proceed now more particularly to set forth and finally claim.

In the accompanying drawings, illustrating the invention, in the several figures of which like parts are similarly designated, Figure 1 is a side elevation, showing the winding-drum and its guiding-pulleys and belt in dotted lines in its forward position to receive the metal from the rolling-mill. Fig. 2 is a top plan view with the carriage in its rearmost position. Fig. 3 is a top plan view in partial section, on a larger scale, showing the gearing for operating the carriage, winding-drum, and attachments. Fig. 4 is a transverse section, on a larger scale, taken substantially in the plane of line A B, Fig. 2, and looking in the direction of the arrow, some of the parts being omitted for clearness. Fig. 5 is a transverse section, on a larger scale, taken substantially in the plane of line C D, Fig. 2, and also looking in the direction of the arrow, some of the parts being omitted for clearness. Fig. 6 is a rear elevation, showing the clutch-shifting

levers for reversing the winding-drum. Figs. 7 and 8 are respectively a plan and an end elevation showing the cam and escapement clutch for shifting the belts and their supporting-pulleys and arms to one side of the winding-drum. Fig. 9 is a top plan view of the sliding clutch-block. Fig. 10 is a longitudinal section of the cam and escapement-clutch. Fig. 11 shows in plan view the escapement-clutch operating-levers separated. Fig. 12 is an elevation, partly in section, showing the manner of mounting the escapement clutch-levers. Fig. 13 is a side elevation of the escapement-clutch levers. Fig. 14 is a plan view of the tension relieving clutch and its operating connections.

Figs. 1 and 2 show the guide-rods, rack-bar and power-shaft broken out to bring the views within the sheet. These parts may be constructed of any length to extend the required distance from the rolling-mill.

1 and 2 represent the rolls of any ordinary sheet-metal rolling mill, and 3 a portion of the frame thereof.

Attached to the frame of the rolling-mill 80 in front of the rolls is a rock-shaft 4 mounted in suitable bearings 5 secured to the frame in suitable manner. A hand-lever 6 is secured to one end of said rock-shaft and is provided with a spring-pawl 7, adapted to engage a 85 rack-bar 8, supported upon a bracket secured to the frame of the rolling-mill, to maintain said lever in its adjusted positions. Arms 9, carrying rollers 10 at their outer ends, are connected with the rock-shaft 4 and project 90 toward the rolls 1 and 2 and are adapted to be moved by said rock-shaft through the movement of the hand-lever 6. Also mounted in suitable bearings 11 upon the frame of the rolling-mill are rock-shafts 12 and 13, 95 provided with upwardly-projecting arms or levers 14 and 15, having at their upper ends flattened friction or contact-surfaces 16 and 17, the arms or levers 14 and 15 being so arranged upon their respective shafts with relation to each other that their contact-surfaces will lie in the path of movement of the rollers 10, and will normally remain open a sufficient distance to receive the rollers 10. Also fixed upon the rock-shafts 12 and 13 are 100 guide-plates 18 and 19 projecting horizontally from the rock-shafts and having their outer ends shaped to fit snugly against the rolls of the rolling-mill, the said guide-plates 18 and 19 being spaced apart sufficiently to 110

permit the passage of the metal between them as it is stripped from the rolls by the edges of said plates. Preferably the guide-plates 18 and 19 are shod with tool-steel pieces 20 and 21 at their points of contact with the rolls of the rolling-mill, to prevent the wearing away of said plates.

Arranged to one side of the rolling-mill and supported in any suitable manner, as by standards 22 and 23, bolted or otherwise secured to the floor of the building, are guide-rods 24 and 25.

Mounted to slide back and forth upon said guide-rods 24 and 25 is a carriage 26 adapted to carry all of the mechanically-driven parts of the coiling mechanism and also the automatic mechanism for moving the carriage toward and from the rolling-mill.

A shaft 27 is arranged parallel with the guide-rods 24 and 25 and mounted in suitable bearings 28 and 29 in the standards 22 and 23, and has secured to it at one end a pulley 30 which may be driven by a belt from a countershaft or any other source of power.

The shaft 27 is grooved longitudinally to receive feathers or splines on the clutch-members, hereinafter referred to whereby said clutch-members may be moved along the shaft by the carriage with the other parts of the operating-mechanism.

A rack-bar 31 is stationarily supported, in any suitable manner, in the standards 22 and 23, in parallelism with the guide-rods 24 and 25, and is adapted to be engaged by a spur-gear, hereinafter referred to, carried by the carriage to move the carriage back and forth upon the guide-rods.

Mounted in suitable bearings in the carriage 26, above the guide-rods 24 and 25, is a shaft 32, carrying a block or winding-drum 33 at its outer end beyond the carriage, and in alignment with the rolls 1 and 2 of the rolling-mill, and fixed to shaft 32 adjacent to the front side of the carriage, is a spur-gear 34.

Supported in suitable bearings in a substantially U-shaped bracket 35, bolted or otherwise secured to the underside of the carriage 26, is a counter-shaft 36, having a spur-gear 37 loosely mounted thereon and meshing with the gear 34 on the winding-drum shaft 32. Mounted on one end of said counter-shaft 36 and fixed thereto is a bevel-gear 38 adapted to be engaged by one or the other of bevel-gears 39 and 40, loosely mounted upon the power-shaft 27, a sliding clutch-member 41 being splined to said power-shaft 27 between said gears 39 and 40, whereby one or the other of said gears may be locked with and rotated by the power-shaft. The gears 39 and 40 are provided with integral grooved collars 42 and 43, respectively, adapted to be engaged by forked brackets 44 and 45 bolted to and depending from the carriage 26,

whereby the gears 39 and 40 are maintained in position upon the power-shaft and also moved along the shaft during the movements of the carriage toward and from the rolling-mill. A foot-lever 46 is pivotally mounted upon a stud 47 projecting from the bracket 35, and has its treadle-portion extending outwardly in convenient reach of the foot of the operator. At its other end said foot-lever 46 is connected by means of a link 48 with a bell-crank lever 49, mounted upon a stud 50, secured to the bracket 35, and having the forked arm 51, Figs. 5 and 6, adapted to engage a groove in the clutch-member 41, whereby the said clutch-member may be shifted into and out of engagement with one or the other of the bevel-gears 39 and 40. A coiled spring 52 is connected at one end to the bracket 35 and has its other end connected to the foot-lever 46, to maintain said foot-lever in an elevated position and normally hold the clutch-member 41 in engagement with the bevel-gear 40, whereby the winding-drum is rotated in the proper direction for coiling the metal.

The spur-gear 37 which, as heretofore stated, is mounted loosely on counter-shaft 36, is provided with an integral flange 53, and mounted to slide upon the shaft 36 is a grooved collar 54 to which are pivoted oppositely arranged links 55, which are connected at their other ends to the operating connections 56 of sliding clutch-shoes 57, adapted to engage the periphery of the flange 53 of the gear 37. The clutch-shoes 57 are slidably mounted, as by dovetail connection 58, in a collar 59, fixed to the shaft 36. Supported in a bearing 60 projecting from the side of the U-shaped bracket 35 is a short vertical rock-shaft 61 having fixed to its upper end a forked lever 62, preferably provided with friction rollers 63, adapted to engage the grooved collar 54, a lever 64 being fixed to the lower end of said rock-shaft 61 having its other end pivotally connected to a link 65, which in turn is connected by a slot and pin connection with a lever 66 projecting outwardly and provided with a suitable upturned handle 67 in convenient reach of the operator. The lever 66 at its other end is connected to a rock-shaft 68 mounted in a suitable bearing 69, formed in a bracket 70, bolted or otherwise fastened to and depending from the rear of the carriage 26. By shifting the lever 66 the clutch-shoes 57 may be caused, by means of the mechanism above described, to engage and disengage the flange 53 of the gear 37.

Mounted in suitable bearings in the carriage 26 are rock-shafts 71 and 72 and a driving-shaft 73. These shafts 71, 72 and 73 are mounted to slide longitudinally in their bearings in the carriage, and are connected to move simultaneously by a plate 74 fitted upon said shafts between the walls of the car-

riage 26 and held in proper position upon the shafts by means of fixed collars 75, 76, and 77, arranged upon the respective shafts on opposite sides of the plate.

5 Fixed to the outer ends of the rock-shafts 71 and 72 are arms 78 and 79, respectively, having belt-pulleys 80 and 81 mounted upon their outer ends, the said pulleys 80 and 81 being preferably provided with central 10 flanges 82 and 83. Secured to the arm 78 in any suitable manner, is a curved guide-plate 84, see Fig. 1.

Fixed upon the rock-shafts 71 and 72 toward the carriage 26 are segmental gears 15 85 and 86, adapted to mesh one with the other for the purpose of transmitting power from one shaft to the other to cause the arms 78 and 79 to move toward and away from the winding-drum.

20 Secured to the outer end of the shaft 73 is a belt-driving pulley 87, similar in construction to the pulleys 80 and 81, and arranged in alinement therewith. A belt or preferably two belts 88 are arranged over the pulleys 80, 81 and 87, and any suitable mechanism for tightening the belts about the driving-pulley 87 may be provided, and I have herein shown two oppositely arranged bell-crank levers 89 and 90 loosely mounted upon 25 the shaft 73, one of the arms of each of said levers projecting from the shaft upon opposite sides and in substantial alinement with each other, and provided with idler or belt-tightening pulleys 91 and 92, adapted to 30 press the belts 88 about the pulley 87 and thus prevent the tendency of said belts slipping, and also taking up any stretch that may occur in said belts. A coiled spring 93 is connected to the ends of the other arms of 35 said bell-crank levers which tends to draw said arms toward one another, and thereby maintains a continuous pressure of the idlers or pulleys 91 and 92 upon the belts 88.

Pulleys 94 and 95 are arranged upon the 40 winding-drum shaft 32 and the shaft 73, respectively, to turn with them, and a belt 96 is arranged upon said pulleys, whereby the power from said winding-drum shaft is transmitted to the belt-driving shaft 73 and its attached pulley 87.

Secured to the rock-shaft 72 is a worm-wheel 97, adapted to be engaged by a worm 98 fixed on the end of a short horizontal shaft 99, suitably supported in a bracket 100 45 fixed to the base of the carriage 26 and having a bevel-pinion 101 fixed to its opposite end, meshing with a bevel-gear 102, secured to the upper end of a vertical shaft 103, mounted in suitable bearings in the carriage 50 26 and at its lower end in a bracket 104, bolted or otherwise secured to the underside of the carriage. Mounted upon the vertical shaft 103 is a spur-gear 105 meshing with the rack-bar 31, whereby the carriage is moved 55 back and forth as hereinafter explained.

Mounted upon the shaft 103 is a worm-wheel 106 meshing with a worm 107, see Fig. 3, carried by a counter-shaft 108 suitably supported in a bracket 109, bolted or otherwise secured to the underside of the carriage. A 70 bevel-gear 110 is fixed to shaft 108 in mesh with bevel-gears 111 and 112, loosely mounted upon the power-shaft 27. The bevel-gears 111 and 112 are provided with integral grooved collars 113 and 114, adapted to be 75 engaged by forked brackets 115 and 116, bolted or otherwise secured to and depending from the carriage 26, whereby said gears are maintained in position upon the shaft, and also adapted to be moved along the shaft in 80 the movement of the carriage to and from the rolling-mill.

A clutch-member 117 is splined to the shaft 27 between the gears 111 and 112, and is adapted to be thrown into engagement 85 with corresponding clutch-faces on one or the other of the gears 111 and 112, to lock one or the other of said gears to the power-shaft to thereby transmit motion to the shaft 108 in the desired direction. 90

Secured to the upper end of the rock-shaft 68 in bracket 70, is a forked lever 118, provided with suitable friction-rollers adapted to engage a groove in the clutch-member 117. Thus it will be observed that by shifting the hand-lever 66, which is connected to the lower end of the rock-shaft 68, the clutch-member 117 may be shifted in either direction to effect the locking of one or the other of the gears 111 and 112 to the power-shaft. 95

Fixed to the shaft 73 is a grooved collar 119, and extending from the carriage to one side thereof is a bracket 120 in which is mounted a vertical rock-shaft 121. A 105 forked lever 122 is fixed to the upper end of shaft 121 and is provided with suitable friction-rollers 123 adapted to engage the groove of the collar 119 on shaft 73. Secured to the lower end of the rock-shaft 121 is an arm 110 124 projecting toward shaft 27, and provided at its outer end with a suitable friction-roller 125, adapted to engage cam-groove 126 in a cam 127 fitted loosely upon shaft 27. The cam 127 is also provided with a straight 115 groove 128, and a recess 129 which extends across said groove 128 and opens at the face of the cam. A sliding clutch-block 130 is fitted in said recess 129 and is backed by a spring 131 in the inner end of said recess. 120 The clutch-block 130 is provided with a transverse bevel-sided notch 132 coinciding with the straight groove 128 in the cam 127. Pivotaly mounted upon a stud 133 secured to a suitable bracket 134, bolted or otherwise 125 secured to the carriage 26, are two escapement or clutch-operating levers 135 and 136, shaped to fit within the straight groove 128 in the cam 127, and having their ends so shaped or tapered, as shown in Figs. 7 130

and 11, as to alternately disengage and engage the notch 132 in the sliding clutch-block 130, during the rotation of the cam, to cause the said clutch-block 130 to be projected from the face of the cam by the action of its spring 131, and to be retracted into its recess by the action of one or the other of the clutch-levers 135 and 136 during every half revolution of the cam. The clutch-lever 135 10 is provided with a roller 137 adapted to be engaged by a cam 138 fixed to the stationary rack-bar 31, when the carriage is about to reach its farthest position away from the rolling-mill. Splined to the shaft 27, adjacent to the cam 127, is a collar 139 having in its face next to the cam a radial groove or notch 140 adapted to be engaged by the clutch-block 130 when projected from the cam upon being released by the action of the 15 cam 138, and thereby locking the cam 127 to the shaft 27 to rotate the same a half revolution when the clutch-block will be retracted and the rotation of the cam stopped for a purpose presently explained. The cam 127 and collar 139 are held in place 20 upon and moved along the shaft 27 by the engagement of the arm 124 and its roller 125 and the escapement or clutch-levers 135 and 136 with their respective grooves in the 25 cam 127, the collar 139 being arranged adjacent to the grooved collar 114 of the gear 112.

Depending from the rack-bar 31 is a bracket 141 having in its lower end an adjustable stop-screw 142, arranged in the 30 path of movement of the hand-lever 66, and in such position that as the carriage approaches its farthest position away from the rolling-mill, the said lever 66 will strike said stop-screw 142 and be shifted thereby and thus throw the clutch-member 117 out of 35 engagement with the gears 111 and 112, and thus stop the carriage-operating mechanism, when the carriage reaches the desired distance away from the rolling-mill.

40 An adjustable stop-screw 143 is fixed to the standard 23 in the path of movement of the projecting end of the link 65, and when the carriage reaches its proper position at the rolling-mill, the end of the link 65 strikes said 45 stop-screw 143 and through its connection with the hand-lever 66 shifts said lever, and thereby throws the clutch-member 117 out of engagement with gears 111 and 112 and thus stops the carriage-feeding mechanism.

50 The operation is as follows: When the carriage and its attached parts are in the position shown in full lines Fig. 1, and power applied to pulley 30 to turn it in the direction of the arrow, Fig. 2, the several parts of 55 the coiling-mechanism, except the winding-drum, will remain motionless, and the arms 78 and 79 and their attached pulleys and belts will assume the position shown in said Fig. 1. When it is desired to coil a strip of 60 metal as it comes from the rolls 1 and 2 of the

rolling-mill, the operator throws the hand-lever 66 to the right, thus throwing the clutch-member 117 into engagement with the bevel-gear 111, causing said bevel-gear to turn with the power-shaft 27 and thereby 70 rotating shaft 108 and its worm 107 through bevel-gear 110, and through worm 107 and worm-wheel 106 rotating vertical shaft 103 and its attached spur-gear 105, and said spur-gear 105 meshing with the rack-bar 31, 75 the carriage will be moved toward the rolling-mill. During the movement of the carriage in this direction, the rock-shaft 72 will be actuated through its worm-wheel 97, worm 98, shaft 99, bevel-gear 101 and bevel-gear 102. By this movement of rock-shaft 72, the arms 78 and 79 and their attached pulleys and belts will be simultaneously shifted, through the segmental gears 85 and 86, to the position indicated by dotted lines at 80 the right in Fig. 1, with the belts 88 partially surrounding the winding-drum 33, leaving sufficient opening between the pulleys and belts in alignment with the exit of the rolling-mill rolls for the passage of the metal there-between. When the carriage reaches this dotted line position, the end of the link 65 strikes the stop-screw 143 and automatically shifts hand-lever 66 and thus throws clutch-member 117 out of engagement with gear 111 90 to a neutral or middle position, and thus stops the carriage feed mechanism. The lever 6 of the stripping and guiding attachment is pulled to the right, and thus forces the rollers 10 in between the friction-surfaces 16 and 17 100 of levers 14 and 15, and by the movement of the rock-shafts 12 and 13, the guide-plates 18 and 19 are forced close up to the rolling-mill rolls and effectually strip the metal therefrom and overcome the tendency of the 105 metal to cling or adhere to the surface of the rolls, and consequently guide the metal to the coiling mechanism. The winding-drum 33 is rotated in the proper direction through its gear 34, gear 37, clutch-members 57, shaft 110 36, bevel-gear 38, and bevel-gear 40 from the power-shaft. The belt 96 and pulleys 94 and 95 connecting the winding-drum shaft 32 and pulley shaft 73, transmit the motion from said winding-drum shaft to the said 115 pulley shaft, and said pulley shaft and the belts 88 applied thereto are driven at a surface speed a little faster than the speed of the metal being wound on the winding-drum, and the belt-tightening pulleys 91 and 92 120 maintain the proper engagement of the belts 88 with belt-pulley 87. As the metal leaves the guides or strippers, it is guided in between the pulleys 80 and 81 and between the belts 88 and the underside of the winding-drum 33, 125 and passes around the drum between the belts and drum, and its end strikes the curved guide-plate 84 and will be automatically and without the operator's intervention guided thereby in between the winding-drum 130

and the first layer of metal as it comes from the guides. This forms the first lap of metal about the winding-drum, and it now becomes necessary to move the carriage away 5 from the rolling-mill in order to inspect the metal as it comes from the rolling-mill, and to effect this movement of the carriage, the operator throws the hand-lever 66 to the left and thereby shifts the clutch-member 117 10 into engagement with the bevel-gear 112 on the power-shaft, thus reversing the gearing heretofore described for moving the carriage to its forward position and returning the carriage to its rearward position, and also re- 15 turning the guiding-belts and their supporting arms and pulleys to the position shown in full lines in Fig. 1. As the carriage approaches its rearmost position, the lever 66 will strike the stop-screw 142 and will be re- 20 retarded in its movement with the carriage, and by the movement of the lever 66 the clutch-member 117 will be thrown out of engagement with the bevel-gear 112 to a neutral or middle position, and the movement of 25 the carriage stopped at the end of its travel.

When the carriage starts away from the rolling-mill rolls after the first lap of metal is wound upon the winding-drum, it becomes necessary to relieve the tension on said 30 metal, due to the pull of said winding-drum. In this connection it is to be noted that the same mechanism drives the winding-drum at all times and in all positions, and when the winding-drum has reached its back po- 35 sition, and is completing the last laps of the coil of metal, the surface speed of said metal in feet per minute is different than when the winding-drum is starting from its for- 40 ward position, and during this movement the drum has the combined operations of winding the coil and at the same time pull- 45 ing against the metal. To relieve this ten- sion on the metal, the pressure of the clutch- 50 shoes 58 on the flange 54 of the gear 37 is slackened when the operator throws the hand- 55 lever 66 to the left in starting the return move- 60 ment of the carriage. By this move- 65 ment of the hand-lever 66, the pin connec- 65 tion in said lever 66 engages the left-hand end of the slot in link 65, thereby pulling upon lever 64 and through forked lever 62 and its operating connections shifting clutch- 70 collar 54 to thereby slacken the pressure of clutch-shoes 58 on the flange 53 of gear 37, and since said gear 37 is loosely mounted on shaft 36 and is driven by said clutch-shoes 58, the slackening of the pressure of said clutch- 75 shoes will allow the gear 37 to slip on said clutch-shoes when the increased tension on 80 the metal occurs due to the combined mo- tions of the carriage and winding-drum. The slipping of the gear 37 will cause said gear to drive the winding-drum only fast 85 enough to maintain a slight tension on the metal as it comes from the rolling-mill, and

just sufficient to hold the first lap of metal on the winding-drum, during the movement of the carriage from its forward position to its back position. As the carriage approaches its back position, the end of link 70 65 will strike the stop-screw 142, and the clutch-mechanism will be reversed and the full pressure of the clutch-shoes again applied to gear 37 to drive the winding-drum at normal speed to finish the winding of 75 the coil, and upon further movement of the carriage, the lever 66 is moved by stop- screw 142 and the clutch-member 117 of the carriage feeding mechanism shifted to stop the carriage as hereinbefore described. 80

The slot and pin connection between the lever 66 and link 65 permits the throwing of the lever 66 to the right for again starting the carriage in its forward movement, without moving the link 65, and thus the pressure of the clutch-shoes 58 on flange 54 of gear 37 is not affected by the movement of the lever 66, and remains constant so as to drive the winding-drum at normal speed, until said lever 66 is shifted to the left to 90 cause the backward movement of the carriage.

When the carriage reaches its back position, the cam 138 on rack-bar 31, strikes roller 137 on clutch-lever 135, thereby rock- 95 ing the clutch-levers 135 and 136, and thus withdrawing the end of clutch-lever 136 from the notch 132 in clutch-block 130, and depressing the end of clutch-lever 135 into the path of movement of the clutch-block 100 130. The clutch-block 130 being thus released is forced by its spring 131 into engagement with the groove 140 in collar 139, and the cam 127 thereby locked to the shaft 27 and rotated thereby. As the cam 127 is 105 rotated, its cam groove 126 moves arm 124 to the left and through rock-shaft 121, forked lever 122 and its connection with fixed collar 119 on shaft 73, moves said shaft 73, and also rock-shafts 71 and 72, through the connecting-plate 74, transversely of the carriage, thereby moving the guide-belts and their supporting arms and pulleys toward the carriage end of the winding-drum, in order that the operator may more easily 115 handle the finished coil of metal upon the drum. When the cam 127 has made a half revolution, the beveled end of clutch-lever 135 engages the notch 132 in clutch-block 130 and retracts said clutch-block and dis- 120 engages it from collar 139 and thus stops rotation of cam 127. When the carriage is started in its movement toward the rolling- mill, the roller 137 on clutch-lever 135 leaves cam 138, and the clutch-levers return to 125 their normal position, the clutch-lever 135 releasing clutch-block 130 and permitting it to again jump into engagement with the notch in collar 139, whereby the cam 127 is rotated to shift the guide-belts and their 130

supporting arms and pulleys to their operative position over the winding-drum. When the cam 127 has made another half revolution, the tapered end of clutch-lever 136 5 engages the notch in clutch-block 130 and disengages it from collar 139 and again stops rotation of the cam 127.

After the metal has been wound upon the winding-drum to form a finished coil, it is 10 found that the coil is wound too tight to be easily removed from the drum, and to overcome this difficulty, provision is made for partially unwinding the coil, enough to loosen it, so that it may be readily drawn off 15 the drum. When the end of the metal being wound upon the drum leaves the rolling-mill, the operator places his hand upon the coil, and when the coil is finished, he then depresses the foot-lever 46 and through link 48 20 and bell-crank lever 49, disengages the clutch-member 41 from bevel-gear 40 and moves it into engagement with bevel-gear 39, thereby reversing the winding-drum driving-mechanism and rotating the winding-drum in the opposite direction, thus 25 loosening the coil, which may then be removed readily from the drum by endwise movement thereof. The foot-lever is then released and the clutch mechanism reversed 30 to again reverse the winding-drum mechanism to rotate the drum in the proper direction for winding or coiling a fresh strip of metal.

The several operations of the machine, as 35 thus described, are repeated in each movement of the carriage toward and from the rolling-mill in winding successive strips of metal, and as the carriage moves upon the guide-rods, the several members of the gearing and their controlling mechanism for operating the parts of the winding-mechanism and for feeding the carriage are simultaneously carried along the power-shaft with the carriage by means of the brackets secured to 45 the carriage and engaging the several members.

It is to be further noted that in the operations of first applying the strip of metal as it comes from the rolling-mill to the winding- 50 drum or block, there is no necessity for the operator to handle the metal at all, but the operation of applying the strip initially to the drum or block, as well as throughout its successive coils, is performed automatically, 55 and hence the danger of injury to the operator, incident to the old way of manually applying the initial coil to the drum or block is overcome, and consequently the work may proceed not only with greater safety, but 60 more expeditiously. Further, the guiding mechanism for applying the strip to the drum is of such character as to insure the uniform coiling of the strip upon the drum.

While I have herein shown and described 65 suitable mechanism for carrying out the

principle of the invention, it is to be understood that the invention is not limited to the single illustration shown, but is obviously susceptible of variations and modifications, as I mean so to claim the invention. 70

What I claim is:-

1. In a machine for coiling metal, the combination of a reciprocating carriage, a winding-drum carried thereon, a blocking device and controlling mechanism therefor operated by the movement of the carriage to lap the leading end of the metal strip upon said drum, and means to effect and control the movements of the carriage in the formation of the first and subsequent laps. 75

2. In a machine for coiling metal, the combination of a pair of rolls, a carriage adapted to be moved toward and from the rolls, means for coiling a strip of metal mounted on said carriage, means for operating the carriage to move it toward and from the rolls, and means operated by the carriage for controlling the carriage operating means. 80

3. In a machine for coiling metal, the combination of a carriage, and means for coiling a strip of metal mounted thereon, reversible gearing for moving the carriage toward and from the metal to be coiled, a lever carried by said carriage for reversing said gearing to start said carriage in its movements, and stationary stops for engaging and shifting said lever by the movement of the carriage to stop the carriage at the end of its travel in both directions. 90

4. In a machine for coiling metal, as it comes from the rolls of a rolling-mill, mechanism for stripping the metal from the rolls of said rolling-mill, a carriage adapted to be moved toward and from said stripping mechanism, a coiling mechanism mounted upon 105 said carriage, including a winding-drum and a power-operated blocking device co-operating with said winding-drum for receiving the metal from said stripping mechanism and forming an initial lap of metal upon said 110 winding-drum.

5. In a machine for coiling metal, as it comes from the rolls of a rolling-mill, mechanism for stripping the metal from the rolls, a carriage adapted to be moved toward and from said stripping mechanism, a winding-drum mounted upon said carriage and adapted to approach said stripping mechanism, a belt and supports therefor mounted upon said carriage and means for moving 115 said supports operated by the movement of the carriage to cause said belt to partially surround said winding-drum when adjacent to said stripping mechanism to guide the metal upon said winding-drum to form an 120 initial lap of metal thereon and to be disengaged therefrom when the carriage and its attached mechanism are moved away from said stripping mechanism to complete the 125 winding of the metal. 130

6. In a machine for coiling metal, as it comes from the rolls of a rolling-mill, mechanism for stripping the metal from the rolls, a carriage adapted to be moved toward and from said stripping mechanism, a winding-drum mounted upon said carriage and adapted to approach said stripping mechanism and means for rotating the winding-drum in winding direction, a belt movably supported upon and carried by said carriage and means operated by the movement of the carriage to move said belt to cause it to partially surround said winding-drum when adjacent to said stripping mechanism to guide the metal as it comes from the rolls to and upon said winding-drum to form the initial lap of metal on the winding-drum, and to be disengaged from said winding-drum by the movement of the carriage when the carriage is moved away from said stripping mechanism to complete the winding of the metal, and means for reversing the winding-drum to partially unwind the finished coil for ready withdrawal from the winding-drum.

25 7. In a machine for coiling metal, as it comes from the rolls of a rolling-mill, mechanism for stripping the metal directly from the rolls, a carriage adapted to be moved toward and from the stripping mechanism, a winding-drum mounted upon said carriage adapted to approach said stripping mechanism and means for rotating said winding-drum, a belt movably supported upon and carried by the carriage, and means operated by the movement of the carriage for moving said belt and its supports to cause the belt to partially surround said winding-drum when adjacent to the stripping mechanism to guide the metal upon said winding-drum to form the initial lap of metal, and to be disengaged from said winding-drum by the movement of the carriage when the carriage is moved away from the stripping mechanism, to complete the winding of the metal, and means controlled by the movement of the carriage to shift said belt and its supports in the direction of the length of said winding-drum.

8. In a machine for coiling metal, as it comes directly from the rolls of a rolling-mill, mechanism for stripping the metal from the rolls, a carriage and mechanism to move it toward and from said stripping mechanism, a rotary winding-drum on said carriage, a blocking device on said carriage and means for operating the same to cause it to coöperate with the winding-drum and the stripping mechanism to aid in receiving the metal from the stripping mechanism and to form the initial lap on the winding-drum, and means for stopping the carriage-moving mechanism when the carriage reaches the extreme of its travel.

9. A stripping and guiding mechanism for metal coiling machines, comprising two rock-

shafts, a pair of plates secured to said rock-shafts and adapted to project toward the rolls of a rolling-mill and fitted to strip the metal from said rolls, crossed arms projecting from said rock-shafts, a rock-shaft arranged adjacent to said first-mentioned rock-shafts, arms fixed and projecting from said rock-shaft and having their outer ends interposed between the crossed arms, and a lever for operating the last-mentioned rock-shaft to force the ends of its arms down between the crossed arms and thereby rock the first-mentioned rock-shafts and force the stripping and guiding plates into close contact with the rolls of the rolling-mill, whereby the metal is stripped from the rolls and guided to the coiling machine.

10. In a machine for coiling metal, the combination of a carriage, a support having guide-rods upon which said carriage is slidably mounted, a winding-drum mounted upon said carriage, a power shaft mounted in said support, means operated by said power shaft to move the carriage along the guide-rods, and means, including a friction clutch, between said power shaft and winding-drum to operate the latter, and to be released to relieve the tension on the metal being coiled upon the winding-drum.

11. A machine for coiling metal, comprising a carriage, a support having guide-rods upon which said carriage is slidably mounted, a winding-drum carried by said carriage, a power shaft mounted in said support in parallelism with said guide-rods, means operated by said power shaft to move the carriage along said guide-rods, said means including a driving member slidably mounted on the power shaft and movable with the carriage, and means also operated from said power shaft and also movable with the carriage adapted to operate the winding-drum, said last-mentioned means including a driving member slidably mounted on the power shaft and also a friction power transmission member between said driving member and the winding-drum.

12. In a machine for coiling metal, the combination with a winding-drum, of a belt, supports for holding said belt away from said winding-drum, means for causing said belt to travel about said supports, and means for moving said supports to cause the belt to partially surround said winding-drum to guide the metal thereon.

13. In a machine for coiling metal, the combination with a winding-drum, of a belt, supports for holding said belt away from said winding-drum, means for causing said belt to travel about said supports in the direction of rotation of the winding-drum, and means for moving said supports to cause the belt to partially surround said winding-drum to guide the metal thereon.

14. In a machine for coiling metal, the

- combination with a winding-drum, of a belt, supports for holding the belt away from the winding-drum, means for causing said belt to travel about its supports, and means for 5 moving said supports to cause the belt to partially surround said winding-drum to guide the metal thereon to form an initial lap, and to disengage the belt from said winding-drum after the formation of the 10 initial lap.
15. A machine for coiling metal, comprising a carriage, a winding-drum and a shaft therefor mounted upon said carriage, guide-rods upon which said carriage is mounted, a 15 power-shaft and a rack-bar parallel with the guide-rods, reversible gearing including gears slidably mounted upon and operated by said power-shaft and gears carried by said carriage meshing with said slidable gears, and a 20 spur-gear carried by said carriage engaging said rack-bar to move said carriage upon said guide-rods, a blocking mechanism, comprising a shaft mounted transversely of the carriage, a pulley fixed to the end of said trans- 25 verse shaft, rock-shafts mounted in said carriage and extending over said winding-drum and provided with arms projecting upon opposite sides of said winding-drum, pulleys mounted upon the ends of said arms, a belt 30 supported upon said pulleys and engaging the pulley on said transverse shaft, a driving connection between the winding-drum shaft and the transverse pulley shaft, meshing segmental gears mounted on said rock-shafts to 35 cause them to move in unison, a worm-wheel on one of said rock-shafts, gearing connecting said worm-wheel with the power-shaft, and means for shifting the reversible gearing to move the carriage forward and backward, 40 and to rock the rock-shafts to cause said belt to partially surround the winding-drum in the forward movement of the carriage and to be disengaged therefrom by the return movement of the carriage.
- 45 16. A machine for coiling metal, comprising a carriage, guide-rods upon which said carriage is mounted, a winding-drum mounted upon said carriage, a power-shaft and reversible gearing connected therewith for rotating said winding-drum and moving said carriage forward and backward upon said guide-rods, levers for reversing said gearing, fixed stops for shifting one of said levers by the movement of the carriage to throw the 50 carriage-moving gearing out of operation to stop said carriage in its forward and backward movements, a belt operated by the movement of the carriage to partially surround said winding-drum to receive and 55 guide the metal upon said drum when the carriage is in its forward position, means controlled by the movement of the carriage for disengaging the belt from the drum when the carriage is moved to its backward position, means for supporting and operating said 60 carriage upon said drum when the carriage is in its forward position, means controlled by the movement of the carriage for disengaging the belt from the drum when the carriage is moved to its backward position, 65 means for supporting and operating said

belt, including shafts mounted in said carriage and longitudinally slidable therein, means for connecting said shafts, a grooved collar fixed to one of said shafts, a cam loosely mounted on the power-shaft, a clutch- 70 collar splined to the power-shaft, a clutch-mechanism carried by said cam, a fixed stop for operating said clutch-mechanism to connect and disconnect said cam and clutch-collar to respectively cause said cam to move 75 with the clutch-collar and effect a half revolution of said cam when the carriage reaches its backward position and to permit a further half revolution of said cam when the carriage leaves its backward position, and 80 lever connections between said grooved-collar and said cam, whereby the belt and its supports are moved longitudinally and to one side of the winding-drum when the carriage is in its backward position and also 85 moved to their operative position when the carriage starts its forward movement.

17. A machine for coiling metal, comprising a carriage, guide-rods upon which said carriage is mounted, a winding-drum mounted upon said carriage, a power-shaft and reversible gearing connected therewith for rotating said winding-drum and for moving said carriage forward and backward upon 90 said guide-rods, levers for shifting said gearing, fixed stops for engaging one of said levers to throw the carriage-moving gearing out of operation to stop said carriage in its forward and backward movements, a belt operated by the movement of the carriage to 95 partially surround said winding-drum to receive and guide the metal upon said drum when the carriage is in its forward position, means controlled by the movement of the carriage for disengaging the belt from the 100 drum when the carriage is moved to its backward position, means for supporting and operating said belt, including shafts mounted in said carriage and longitudinally slidable 105 therein, means for connecting said shafts, a grooved collar fixed to one of said shafts, a cam loosely mounted on the power-shaft, a sliding clutch-block fitted in said cam, pivoted clutch-levers adapted to alternately engage and disengage said sliding clutch-block 110 to move it in and out of said cam, a clutch-collar splined to the power-shaft adjacent to said cam and adapted to be engaged by said sliding clutch-block, a stationary member adapted to shift said clutch-levers when the 115 carriage reaches its backward position to alternately release and retract said clutch-block to thereby connect and disconnect said loosely mounted cam and clutch-collar to effect a half-revolution of the cam, and also 120 to effect a further half revolution of the cam when said clutch-levers are disengaged from said stationary member by the movement of the carriage toward its forward position, and lever connections between said grooved col- 125 130

lar and said loosely mounted cam, whereby the belt and its supports are moved longitudinally and to one side of the winding-drum when the carriage is in its backward position 5 and also moved to their operative position when the carriage starts on its forward movement.

18. A machine for coiling metal, comprising a carriage, guide-rods upon which said carriage is mounted, a winding-drum mounted upon said carriage, a power-shaft and operating gearing connected therewith for rotating said winding-drum and moving said carriage forward and backward upon said 10 guide-rods, a belt coöperating with said drum to guide the metal thereon, means for supporting the belt, means controlled by the movement of the carriage for operating the belt-supporting means to cause the belt to 15 partially surround the winding-drum when the carriage is moved forward, and to be disengaged therefrom when the carriage is moved backward, and a guide-plate carried by the belt-supporting means and adapted 20 to deflect the end of the first lap of metal be- 25

ing wound between the said winding-drum and the metal itself.

19. In a machine for coiling metal, a winding-drum, a power-shaft and gearing thereon for rotating the winding-drum, a belt coöperating with the winding-drum to guide the metal thereon, means for movably supporting the belt, a cam loosely mounted on said power-shaft, a sliding clutch-block fitted in said cam, a clutch-collar splined to the power-shaft adjacent to the cam, and means adapted to alternately engage and disengage said sliding clutch-block to cause it to engage and disengage said clutch-collar to thereby rotate the cam, and connections between the cam and the belt-supporting means to move the belt and its supporting means longitudinally of the winding-drum. 30 35 40 45

In testimony whereof I have hereunto set my hand this 3d day of January, A. D. 1908.

EDWARD O. GOSS.
